CLARK S. HUTCHINSON, OF BURLINGTON, NEW JERSEY.

Letters Patent No. 87,261, dated February 23, 1869.

IMPROVEMENT IN MACHINES FOR MAKING TAGS.

The Schedule referred to in these Letters Patent and making part of the same.

To all whom it may concern:

Be it known that I, CLARK S. HUTCHINSON, of Burlington, in the State of New Jersey, have invented a new "Machine for Making Tags and Labels;" and I do hereby declare the following is a full and exact description thereof, reference being had to the accompanying drawings, and to the letters of reference marked thereon.

The nature of my invention consists in constructing a machine which will make tags, or labels from one continuous ribbon of paper.

My machine folds over the edge of paper required for the tag, inserts a tape, strips of fibre, or a cord, or both tape and cord at the same time; gums the fold down upon the tape, punches the eyelet, prints the address, and cuts the tag the required width, in one continuous operation.

To enable others skilled in the art to make and use my invention, I will proceed to describe its construction and operation.

Figure 1 is an elevation, mostly in section.

Figure 2 is a plan.

Figure 3 is an end view.

Figure 4 is the sliding wedge detached.

A is the frame of the machine.

B B', the reel on which is wound the ribbon of paper, a.

The side-plate B' is movable endwise, on spindle, a', to accommodate the width of paper required for the tags.

C is a guide for giving direction to the paper.

D D, a pair of rollers, the upper one having a flange, d, fitting into a corresponding groove in the lower roller. This flange and groove crease the paper in the proper line at which it is to be bent, and the upper roller, being shorter than the lower one, permits the flanged edge of the paper to bend up nearly at right angles.

The guide, d', further assists in giving the flange d a perpendicular direction.

The rollers D may be brought into closer contact by screws, d', acting on their bearings.

E is a pan, filled with paste, or mucilage, e.

e' is a reel, carried by an arm, e', which is hinged to the pan E, at e'.

The arm e' is continued down into the tank, or pan E, nearly to the bottom, at e'.

The reel e' has wound on it the cord, or tape, e', to be inserted in the tag.

e' is a plate on the side of the pan, through which tape e' passes, and is scraped of surplus mucilage.

The reel e' swings upon the hinge e', so that the guiding-rod e' may be lifted out of the tank for the adjustment of the tape beneath the rod e'.

G is a small guide-roller, for giving direction to the tape e', and

g', a bent strip of metal, pressing the tape in its place, and equally distributing the mucilage.

O C are guides, made to move in and out, on sliding forks C', to prevent them from twisting.

H is a strip of metal, so curved as to turn over the bent perpendicular edge of the tag, and fold it down flat upon the tape.

The spring-bar h is hinged at its centre, one end resting upon the fold, its pressure being regulated by an adjustable screw, h', at the opposite end.

J J' are a pair of feed-rollers, geared into each other at J'. They draw the paper from reel B, and force it forward. The upper roller is adjustable in its bearing, so as to nip the ribbon or paper. It is cut away at J', to permit the extra thickness of the fold to pass through. These rollers also have flanges, J', on opposite ends.

Motion is given to the feed-rollers in this way:

K is the main driving-shaft of the machine, having on it a cam, k', which, in its upward motion, strikes against the arm k', and elevates the upright bar k', which slides in guides at the top and bottom.

To the bar k' is hinged a link, k', and that is jointed to another small link, k'', which is pivoted to the shackle k'.

The shackle k' embraces both sides of the wheel k'', and the elevation of the link k' causes the shackle to bite on the opposite points of the wheel k'', and give the requisite motion to the feed-rollers.

Spring k'' maintains the action of the shackle more uniform.

Spring k''' reverses the motion of the shackle k' if the weight of the rod k'' is not sufficient.

The arm k' is adjustable vertically, by screws k'', to regulate the stroke. The feed-rollers might also be operated by a pawl and ratchet, but this motion is not quite so regular.

L is the knife or shears, fitting in a frame, l, and sliding up and down vertically, in guides l'. The lower end of frame l is extended into a fork, l'', embracing the shaft K. This fork carries on it a stud and roller, l', which works in a groove in cam M, thus giving motion to the knife L, which is kept in close-fitting contact with its corresponding blade l'', by means of screw l'. The lower blade, l'', is secured rigidly to guide l'.

m' is an angle-piece, cast on frame l, and, by screws m'', the type-box m is secured to it, so that the type m' is adjustable over the exact spot on the tag. The type partake of the same motion as the shears L.

N is the inking-roller, pivoted in frame n, which is hinged, at n', to a sliding guide, n''. This sliding guide runs in a groove, in frame O. This frame, O, carries two inking feed-rollers, o' o'', for supplying ink to roller N. They are rotated by a band, o'', operated from the main shaft, K. The connecting-rod p is jointed to the sliding guide n'' at one end; the other, to a vibrating arm, p', which is keyed on shaft p''. To the other end of shaft p'' is keyed another arm, p'', and, secured on this arm, is a triangular tappet, p''. The pointed cam, R, strikes this tappet, and thus gives motion to the inking-roller, N. The spring r gives the reverse motion to the inking-roller.

S is the punch for making the holes through the end of the tag.

s' is the stop, which receives the thrust of the punch. It is bolted to the plate V, which is bolted to the frame A, and is adjustable by bolts, v', to suit the position of the hole to be punched. The punch S passes through a hole cut in said plate V. The punch has on it a col-

lar and nut, and is bolted to the forked bar s^2 . Thus it can be removed and sharpened, or its position changed to suit the width of tag. The bar s^2 runs in guides, s^3 s^4 , at top and bottom. The upper guide, s^3 , and the lower one, also, are adjustable by bolts, which fit into frame A. Thus the punch S can be moved sufficiently to be placed in a central position, for any size of tag required. The pressure to the punch is given by a cam, T, upon the bars of wheel M. This cam, T, strikes a sliding wedge, t, (see fig. 4,) set in a proper position, by screw t', to give the exact pressure required to perfect the hole in the tag.

The operation of the machine I will now briefly recapitulate.

The ribbon of paper is wound upon reel B, from which it is drawn at a regular motion of the feed-rollers J. The guides C steady it, in its onward course, in a direct line. The rollers D, flange it and crease it. The guide d turns the flange d^2 up at right angles. The reel e' has on it the tape e', or a cord, also. Both, or one, or neither, can be used at option. In using the tape, carry one end down under guide e', through the mucilage e, up, through scraper e', down again, under roller G, then under guide g', where it is pressed down to the paper; and, as it passes forward, the flanged edge is folded down over it by the folder H, and is pressed firmly down by spring presser-bar h. It then passes between feed-rollers, J, and on, between the plate V and stop s', and the hole is punched. At the proper interval of time, the inking-roller N passes under the type m', and recedes again. The type descends with the knife and prints the tag, and the knife L cuts off the tag complete. A piece of strong paper strips may be used instead of the tape, or the flanged edge may be gummed, without any tape being used; or a ribbon of paper and cloth, combined in one article, may be used instead of the paper ribbon. These would only be modifications of the same general design herein described.

The same machine will also make business-cards, if the folding and gumming-operation is omitted.

What I claim as my invention, and desire to secure by Letters Patent, is—

1. The tag-machine, herein described, for making finished tags from a continuous strip of ribbon-paper, by the intermittent feed-motion, adjustable punch S, printing-device m', and reciprocating knife L, or their equivalents, arranged and operating in combination, substantially as shown and described.

2. The glue-tank E, in combination with the hinged bracket or arm e', with or without the reel e', so arranged as to pass the fibre e' through the tank, for the purpose specified.

3. The guide-roller G and strip g', combined and operating for the purpose specified.

4. The folder H, in combination with the regulating-pressure spring h, for the purpose described and specified.

5. The intermittent feed-rollers J J', with flanges J', and depression J'' in the upper one, operating as shown and described.

6. The friction-shackle k', embracing both sides of the wheel k', in conjunction with cam-link k', and bearing upon the two opposite points of the circumference, for giving an intermittent feed-motion, as shown and described.

7. The punch S, operating substantially as shown, and being adjustable to the required position, according to the size of the tag, as and for the purpose described.

8. Folding and pasting down the edge of a strip of ribbon-paper, a, with the fibre e', by means of the creasing-rollers D, the glue-tank E, guide-roller G, and folder H, or their equivalents, in combination with the intermittent feed-motion and punching and cutting apparatus, herein described, for completing a finished tag at one operation, substantially as shown and described.
